UNITED STATES PATENT OFFICE.

JOSEPH L. HERZOG, OF NEW ROCHELLE, NEW YORK.

DESIGN FOR A FINGER RING OR SIMILAR ARTICLE.

Application filed January 21, 1921. Serial No. 439,030. Term of patent 14 years.

To all whom it may concern:

Be it known that I, JOSEPH L. HERZOG, a citizen of the United States, residing at New Rochelle, county of Westchester, and State of New York, have invented a new, original, and ornamental Design for a Finger Ring or Similar Article, of which the following is a specification, reference being had to the accompanying drawings, forming part hereof.

In the drawings Fig. 1 is a side view and Fig. 2 is an edge view of the ring embodying my design. An important element of my invention is the unique contrasting color effect between the platinum color of the

raised circumferential band and the contrasting gold color of the remaining portions of the ring.

While I have shown my design embodied by way of example in a ring, I want it to be understood that the application of the design is not limited to rings of the type shown, as it may obviously be embodied in other articles of jewelry such as solitaires, bar pins, scarf pins, bracelets and the like.

I claim:

The ornamental design for a finger ring or similar article, substantially as shown and described.

JOSEPH L. HERZOG.
